UNITED STATES PATENT OFFICE.

JOSEPH LEDWINKA, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

GUIDE FOR SLIDING WINDOWS.

Application filed August 16, 1921, Serial No. 492,768. Renewed April 4, 1927.

My invention relates to improvements in guides for sliding windows and has to do, more particularly, with guides for sliding "sashless" windows, such as are used in the 5 sides and doors of automobile bodies. These "sashless" windows comprise a pane of glass, which is guided at its edges, so that it may be raised from or lowered into a window pocket in the door or the side of the body. The 10 edges of the pane of glass are usually guided in channels in the window frame, to the sides of which channels strips of felt, or similar cushioning material, are tacked so as cushion the pane of glass and absorb the 15 vibrations. These channels are customarily made wide enough and the felt yields enough to permit the lateral movement of the sash relative to the frame, incidental to the raising or lowering of the sash. This guide construction has proven objectionable in practice for the reason that, when the felt or 20 glass becomes wet as, for instance, from the rain, the felt tends to stick to the glass and, hence, tears away from its fastenings and 25 wedges in the channel, preventing the proper sliding of the window.

The leading object of this invention is to provide an improved window guide which will cushion the glass and, nevertheless, 30 avoid the objections heretofore noted.

Another object of this invention is to provide a channel or window guide which is made of felt or similar cushioning material, so reinforced that the guide is self-sustaining 35 and will keep its shape although yielding sufficiently to cushion the pane of glass and permit the necessary lateral movement incidental to raising or lowering the glass.

Further objects, and objects relating to details and economies of operation and construction, will definitely appear from the detailed description to follow. My invention is clearly defined and pointed out in the appended claims. A structure, constituting a 45 preferred embodiment of my invention, is illustrated in the accompanying drawing, forming a part of this specification, in which:

Fig. 1 is a view in elevation of an automobile door having a window frame embodying my invention, part of the window frame being broken away to show the window guide.

Fig. 2 is an enlarged, sectional view on the line 2-2 of Fig. 1.

Fig. 3 is a sectional view on the line 3-3 of Fig. 1.

Fig. 4 is a transverse section through a slightly modified form of window guide.

Fig. 5 is a transverse section through a strip of material, made in accordance with my invention, illustrating by dotted lines the formation of a window guide channel from the strip, and

Fig. 6 is a transverse section through a slightly different embodiment of my invention.

In the drawings, similar reference numerals refer to similar parts throughout the several views and the sectional views are taken looking in the direction of the arrows at the ends of the section lines.

In general, my invention consists in providing a channel, for receiving and guiding the edges of the window glass, consisting of a flexible metallic core surrounded and enclosed by a layer or coating of felt or similar cushioning material which is securely attached to the flexible metallic core. In practice, I use flexible wire screening as the metallic core which may be bent to the desired channel cross-section after which the fibrous material may be deposited upon it so as to build up the layers of felt surrounding the metallic core. If desired, these layers of felt may be built up on the strip of wire 75 screening forming the metallic core, while it is flat, after which the core and felt may be bent to form the channel. In some cases it may be desirable to form the metallic core to channel shape and then cover it by one 80 or more layers of previously prepared felt, folded around the core and secured thereto in any suitable manner, as, for instance, by stitching at intervals.

In the drawings, I have illustrated an embodiment of my invention applied to guide the sliding window glass of an automobile door. The door, 10, includes a window frame, 11, with bead, 12, extending inwardly from the inner edge of the frame. In the lower part of the door, there is provided a pocket or well, 13, into which the window, 17, is dropped when it is lowered. A hook, 15, is fastened to the lower part of the window, 17, and engages the fence, 14, on the frame to support the window in its raised position. A lifting strap, 16, is secured to the lower edge of the window for convenience

in raising and lowering it. It will be observed that, to lower the window from the position shown in Fig. 2, it must be raised and moved laterally to permit the hook, 15, to clear the fence after which the window can be dropped into the well, 13. The window, 17, has no sash and consists merely of a pane of glass, the edges of which are received and guided in a channel secured to the window frame between the bead, 12, and the molding strip, 18. The construction which I have just described is the usual or customary construction and forms no part of my invention which relates to the construction of the channel for guiding and receiving the edges of the window glass.

In order to permit the lateral movement of the glass in raising or lowering, it is desirable that the window guide or channel yield laterally but, at the same time, it should maintain its shape and hug the edge of the glass so as to cushion the glass and keep it from breaking under vibration. Furthermore, the window guide or channel should be self-sustaining and not stick to the glass or wedge out of shape when the glass is wet. I have found the construction illustrated to be very satisfactory from those standpoints. The channel has a flexible, metallic core consisting of a strip of wire screening or mesh, 19, bent to the channel shape and covered by one or more layers of felt, 20, deposited or built up on the core, 19. When the fibres of the layer, 20, are felted or deposited directly on the wire mesh core, 19, they become anchored in it so securely that the felt covering, 20, is very firmly attached to the core, 19.

In Fig. 4, I have shown a modified form of channel or window guide in which the flexible, metallic core, 21, formed in channel-shape of wire mesh or screening, is covered by a layer of previously prepared felt, or similar cushioning material, folded around and secured to the core. Thus the felt is positioned, at 22 and 23, along the bottom and one side of the core channel, is folded, at 24, around the outside of the channel, laid along the inside of the channel, at 25, and, at 26, lapped over the portion, 22, on the bottom of the channel. This covering or envelop of felt may be secured in place on the flexible, wire mesh core, 21, by rows of stitching, 27, through the bottom of the channel. Of course, the felt might be lapped around the core in other ways, the one shown being merely illustrative.

In Fig. 5, another modified construction is shown. In this form, the felt, 29, is deposited on the strip of wire mesh, 28, forming the core, while it is flat. The felt is so laid on the core as to leave the longitudinal grooves, 30, which permit the bending of the felt-covered core to the channel form, as shown by dotted lines in Fig. 5.

In Fig. 6, I have shown an embodiment of

my invention which is very desirable from a practical standpoint, as it can be manufactured very easily. In this embodiment, a channel, 32, is formed from a strip of felt. This may be milled out of a solid piece of felt, if desired. In the legs of the channel, there are formed the slots or kerfs, 33, and the legs have the tail portions, 34, extending rearwardly a slight distance beyond the base. A channel, 35, is formed from a strip of wire mesh and the legs, 36, are inserted in the slots, 33, so that the base of channel, 35, rests on the rear face of the base of the felt channel, 32. A strip, 37, of felt is then applied to the base, 35, between the tail portions, 34, and glued or otherwise secured in such position. This forms a simple and cheap construction in which the channel-shaped, flexible metallic stiffening core is entirely surrounded by the felt.

The window guide or channel, constructed as described, is secured to the frame, 11, between the bead, 12, and the molding strip, 18, and in line with the edges of the pane of glass. This may be effected by screws or nails passing through the bottom of the channel. The guide made as described, yields sufficiently to permit lateral movement of the glass and yet it always maintains its shape and hugs the edge of the glass so as to cushion it effectively. Furthermore, the felt covering is so securely attached to the metallic core that it will not pull out of shape, even when the glass is wet and sticky. I have shown my invention in connection with a window and frame including a fence but, of course, it is not to be so limited or restricted, as it may be used with other types of windows.

I am aware that the embodiment shown and described may be varied considerably without departing from the spirit of my invention and, hence, I claim the same broadly as indicated by the appended claims.

Having thus described my invention, what I claim as new and desire to secure by Letters Patent is:—

1. A guide for a sliding window glass comprising a channel-shaped, flexible, foraminous core surrounded by one or more layers of fibrous cushioning material secured to said core.

2. A guide for a sliding window sash comprising a channel-shaped, flexible, wire-mesh core surrounded by one or more layers of felt secured to said core.

3. A guide for a sliding window sash comprising a channel-shaped, flexible strip of wire mesh, a layer of felt lapped around said strip to enclose the same, and means for securing said felt to said strip.

4. In a device of the character described the combination of a metallic member having substantially continuous outer edges and a body portion of open character with a

covering member of a flexible character, said members being bent to form a channel, and a glass member adapted to fit within said channel, said metallic member holding said glass member by a spring action while permitting the retention by the covering member of its pliability to enable it to adapt itself to different conditions of use.

5. A guide for a sliding window glass comprising a channel-shaped flexible reticulated metallic member surrounded by one or more layers of fibrous cushioning material secured over the same.

In testimony whereof, I affix my signature.

JOSEPH LEDWINKA.
